INK CARTRIDGE

William F. Utzinger, Kettering, Ohio, assignor to
Monarch Marking Systems, Inc., Dayton, Ohio

Filed Sept. 9, 1974, Ser. No. 503,024

Term of patent 14 years

Int. Cl. D18—02

U.S. Cl. D64—10

FIG-1

FIG-2

FIG-3

FIG-4

FIG-5

FIG-6

FIG. 1 is a perspective view of an ink cartridge showing my new design;

FIG. 2 is a top plan view;

FIG. 3 is a bottom plan view;

FIG. 4 is a left side elevational view;

FIG. 5 is a front elevational view; and

FIG. 6 is a rear elevational view.

I claim:

The ornamental design for an ink cartridge, substantially as shown.
